UNITED STATES PATENT OFFICE.

GEORGE J. SCHNEIDER, OF DETROIT, MICHIGAN, ASSIGNOR TO AMERICAN ELECTRICAL HEATER COMPANY, OF DETROIT, MICHIGAN, A CORPORATION OF MICHIGAN.

ELECTRIC HEATING ELEMENT.

No. 863,454.

Specification of Letters Patent.

Patented Aug. 13, 1907.

Application filed July 9, 1906. Serial No. 325,295.

To all whom it may concern:

Be it known that I, GEORGE J. SCHNEIDER, a citizen of the United States of America, residing at Detroit, in the county of Wayne and State of Michigan, 5 have invented certain new and useful Improvements in Electric Heating Elements, of which the following is a specification, reference being had therein to the accompanying drawings.

It is the object of the invention to obtain a construction of an electric heating element, in which the heat generated in the resistance is conducted away rapidly and uniformly from all portions thereof, and is distributed in a body of considerably greater mass. This, on the one hand, prevents the destruction of the 10 element through the over heating of a portion of the resistance, and on the other hand facilitates the application of the heat to the point desired, it being either conducted or radiated from the body in which it is first distributed.

20 To this end, the invention consists in the construction as hereinafter set forth.

In the drawings, Figure 1 is a plan; Fig. 2 is an end elevation of the heating element; Fig. 3 is an elevation of the several members constituting the heating unit detached; Fig. 4 is a longitudinal section of 25 said members assembled but unclamped; Fig. 5 is a section elevation of Fig. 4; and Fig. 6 illustrates a slightly modified construction.

Electrical heaters designed for use with the 30 commercial electrical currents ordinarily available are necessarily of comparatively high resistance. In order to obtain the proper resistance in a small space, the cross section of the conductor is limited, and as a consequence a very slight cause is sufficient to break the 35 circuit; for instance, if some portion of the conductor is in less perfect heat conducting contact with the insulator covering, the heat generated at this point will accumulate, and so cause a "burn out". With the present invention this difficulty is avoided, by placing 40 all portions of the resistance in heat conducting proximity to a body of sufficient mass to act as an equalizer. Furthermore, a comparatively high resistance is obtained by using a conductor offering a, tortuous course for the current in adjacency to the said heat 45 absorbing body.

As illustrated in Figs. 1 and 2, A are heating units, and B are heat absorbing elements, which are arranged alternately in series. The heating units A are formed of electrical conductors arranged to pass the current 50 back and forth, or through a tortuous course, and this conductor is insulated from the adjacent heat absorbing bodies by thin plates of suitable material, such as mica.

To obtain the necessary resistance, I preferably form 55 the conductor of very thin metallic plates or metal

foil, and arrange a series of these plates in parallel planes separated from each other merely by a thin strip of mica. Thus the thickness of the combined plates and insulators in the series is so limited that the heat generated in the resistance may readily pass by conduction into the adjacent heat absorbing body B.

To further increase the resistance, I preferably slit the conductor plates so as to cause the current to pass back and forth through a path of much greater length than the major dimension of the plate. This, as 60 illustrated in Fig. 3, may be accomplished by forming slits a and b extending alternately from opposite edges of the metallic plates c and diminishing the cross section of the conductor, through which the current passes. A series of these plates is then formed with intervening 65 mica insulator plates d, which are arranged to permit the adjacent metallic plates to come into contact alternately at opposite ends. The series is then clamped by suitable means, such as the bolts C, which pass through aligned apertures in the conductor plates, insulators, and the heat absorbing bodies B, and exert a tension combining all of the parts together.

Danger of short circuiting through the clamping bolts C is avoided by covering said bolts with an insulator sleeve D, and to avoid the possibility of turning the 80 edges of one of the conductors across the intervening insulator, I preferably employ the construction illustrated in Fig. 3. In this the metallic plates upon opposite sides of the insulator are provided with polygonal apertures for the bolts, and these apertures are shaped 85 to be out of exact registration although concentric with each other. Thus the portions of one of the metallic plates which are in contact with and are centered by the bolts C, are arranged opposite spaces e in the adjacent metallic plate, and therefore if the conducting 90 edge of one of the metallic plates is drawn across the intervening insulator, it will not short circuit with the adjacent plate.

When clamping pressure is applied to the series, the exposed ends f of the metallic plates will be pressed 95 into contact with each other or the adjacent body B, and in this manner a continuous circuit is established, not only through the series of plates constituting a unit, but also the series of alternate units and heat absorbing elements B. Thus the resistance of the entire circuit 100 may be made as high as desired.

In operation, the heat generated in all portions of the conductor finds an easy path of escape through the thin insulation strips into the bodies B, and from the latter is distributed by conduction or radiation. The 105 clamping pressure is sufficient to prevent the formation of air spaces adjacent to any portion of the conductor, so that the distribution of heat therefrom to the bodies B is by conduction and not radiation. Thus the over heating of this part of the circuit is prevented.

In Fig. 6 a modification is shown in which the resistance element is formed by a wire conductor h mounted about a mica strip and insulated from adjacent resistances, or the heat distributor by intervening mica strips. The members are then clamped together, as in the construction previously described.

What I claim as my invention is:

1. An electrical heating unit comprising a series of alternately arranged laminated conductors and insulators, the opposite ends of adjacent insulators being cut away for permitting direct contact of alternate pairs of adjacent conductors at opposite ends whereby a continuous circuit is formed through the series, and means for clamping the series to bring all portions thereof in mechanical contact.
- 15 2. An electrical heating unit comprising a series of alternately arranged laminated conductors and insulators, a clamping rod passing through aligned apertures in said plates, the apertures in adjacent conducting plates, being out of exact registration to prevent short circuiting therebetween.
- 20 3. An electrical heating element comprising a series of alternately arranged thin flat conducting plates and insulators, means passing through said plates for clamping the series to press the members thereof into close contact, and means for preventing said plates from contacting with each other adjacent to said clamping means.
- 25 4. An electrical heating element comprising a series of alternately arranged thin flat conducting plates and insulators, said conducting plates being slit to cause the current to pass tortuously therethrough, and bolts passing closely through said insulators and loosely through said plates for clamping the series to press said plates into close contact with each other.
- 30 5. An electrical heating element comprising a series of alternately arranged metallic foil conducting plates and thin flat insulators the alternate insulators being short-

ened at opposite ends to permit the contacting of the adjacent conducting plates alternately at opposite ends to form a continuous circuit through the series, and means for clamping the series to press the adjacent plates into close contact.

6. An electrical heating element comprising a series of alternately arranged resistance elements and heat distributor 45 plates, each resistance element comprising a series of alternately arranged thin conducting plates and insulator plates, said conducting plates being folded over and connected at opposite ends to form a continuous circuit through the series of the unit, and said units being electrically connected through the intermediate heat distributor.

7. An electrical heating element comprising a series of alternately arranged resistance elements and heat distributor 50 plates, each resistance element comprising a series of alternately arranged thin flat conducting plates and insulators, an insulated rod passing through aligned apertures in the members of the series for clamping the same in close mechanical contact, and means for preventing the contact of said plates with each other adjacent to said rod.

8. An electrical heating element comprising a series of 60 alternately arranged resistance elements and heat distributor, each resistance element comprising a series of alternately arranged conducting plates and insulator plates, adjacent conducting plates being alternately connected at opposite ends to form a continuous circuit 65 through the series, and adjacent series electrically connected to opposite ends of the intermediate heat distributor.

In testimony whereof I affix my signature in presence of two witnesses.

GEORGE J. SCHNEIDER.
